UNITED STATES PATENT OFFICE.

JOAH BROGDEN, OF PHILADELPHIA, PENNSYLVANIA, ASSIGNOR TO DAVID LUPTON'S SONS COMPANY, OF PHILADELPHIA, PENNSYLVANIA, A CORPORATION OF PENNSYLVANIA.

JOINT FOR SASH-BARS.

1,225,727.

Specification of Letters Patent.

Patented May 8, 1917.

Application filed July 28, 1913. Serial No. 781,467.

To all whom it may concern:

Be it known that I, JOAH BROGDEN, of Philadelphia, in the county of Philadelphia and State of Pennsylvania, have invented 5 certain new and useful Improvements in Joints for Sash-Bars, whereof the following is a specification, reference being had to the accompanying drawings.

The invention relates more particularly 10 to metal sash bars which are made by dividing one of said bars in sections and providing the ends of the sections with projecting parts which are adapted to extend through a mortise formed in the tongue of the other 15 bar.

An object of the invention is to provide a sectional sash bar which may be cheaply made, and which sections, when assembled, are firmly held together, thus making up a 20 strong and durable metal sash.

In the accompanying drawings, which show one embodiment of the invention, Figure I, is a plan view of a section of a metal sash embodying the improvement.

Fig. II, is a transverse sectional view on the line II, II, of Fig. I.

Fig. III, is a transverse sectional view on the line III, III, of Fig. II.

Fig. IV, is a sectional view on the line IV, 30 IV, of Fig. II.

Fig. V, is a perspective view of the end of one section of the divided bar.

Fig. VI is a perspective view of the end of the other section of the divided bar.

In carrying out the invention, one sash bar is provided with a tongue mortised at the point where the other sash bar is to be joined and cross the first sash bar. The other sash bar is divided transversely so as 35 to form abutting ends, adapted to rest against the side faces of the tongue of the first sash bar, and with projecting portions adapted to pass through the mortise in the tongue. These projecting portions lie in 40 the same plane and are of the full thickness of the tongue of the sash bar. The projecting portions are so spaced that one lies above the other when they are projecting through the mortise in the tongue of the 45 other bar.

Each projecting portion of the divided sash bar is formed with interlocking means, whereby two sections may be firmly secured together.

Referring more in detail to the drawings, 50 the sash bar 1, is provided with a tongue 2,

having a mortise 3, extending therethrough. The other sash bar is divided so as to form two sections 4, and 5. The upper portions of the sections are formed as in the usual manner, so as to properly join the upper 60 portion of the other sash bar. The end of the divided section 4, is formed with an abutting portion 6, adapted to engage the side face of the tongue 2, of the sash bar 1, while the end of the section 5, is provided 65 with an abutting portion 7, which engages the other face of the tongue 2. The section 4, is also provided with a projecting portion 8, while the section 5, is formed with a projecting portion 9. These two projecting 70 portions are of the full thickness of the tongue, and are so disposed that one passes through the mortise 3, above the other. The end of the section 4, is cut away as at 10, to receive the projecting portion 9, on the section 75 5. The section 5, is formed with semi-circular recesses 11, and 12, which are adapted to register with semi-circular recesses 13, and 14, respectively formed in the projecting portion 10. When the two sections 4, 80 and 5, are properly assembled with the projecting portions extending through the mortise 3, rivets 15, are passed through the registering recesses 11, 13, and 12, 14, and these rivets serve to hold the projecting portions 85 from being withdrawn from the mortise in the sash bar 1.

From the above construction it will be apparent that I have provided a metal sash bar which may be readily rolled and formed, 90 and, therefore, cheaply made. When the sections of the divided sash bar are in place and secured together, I have a very durable metal sash bar.

It is obvious that minor changes in the 95 details of construction and the arrangement of parts may be made without departing from the spirit of the invention, as set forth in the appended claims.

Having thus described my invention, I 100 claim:

1. A joint for metal sashes comprising crossing bars, one of which has a mortised tongue, and the other of which is divided transversely, forming sections, the end of 105 each section having a portion adapted to abut against the side faces of the tongue of the other cross bar, and a projecting portion extending through said mortise, said projecting portions being the full thickness 110

of the tongue of the sash bar, and lying one over the other and filling said mortise, the adjacent faces of said projections having registering recesses adapted to receive locking members for holding said sections together and in assembled relation with the other cross bar.

2. A joint for metal sashes comprising cross bars one of which has a mortised tongue, 10 the mortise being located at a point above the lower edge of the tongue and the other of which is divided transversely forming sections the end of each section having a portion adapted to abut against the side 15 faces of the tongue of the other cross bar be-

low the mortise, said projecting portions being the full thickness of the tongue of the sash bar and lying one over the other in and filling said mortise, the adjacent faces of said projections having spaced registering 20 recesses adapted to receive locking rivets for holding said sections together and in assembled relation with the other cross bar.

In testimony whereof, I have hereunto signed my name at Philadelphia, Pennsylvania, this 24th day of July, 1913.

JOAH BROGDEN.
